Specification for Design.

Patented Oct. 25, 1921.

Application filed June 18, 1921. Serial No. 478,745. Term of patent 7 years.

To all whom it may concern:

Be it known that I, EDWARD L. WEED, a citizen of the United States, residing at the city of Providence, county of Providence, and State of Rhode Island, have invented a new, original, and ornamental Design for a Charm, reference being had to the accompanying drawing, forming a part thereof.

Figure 1 is a perspective view, showing the casing parts closed, of a charm, illustrating my new design.

Fig. 2 is a perspective view, showing the casing parts in open position, of a charm, illustrating my new design.

I claim:

The ornamental design for a charm, as shown.

EDWARD L. WEED.
